UNITED STATES PATENT OFFICE.

THOMAS D. CATON, OF GEORGIANA, ALABAMA.

FOWL ROOST.

Application filed November 5, 1925. Serial No. 67,055.

This invention relates to improvements in fowl roosts, particularly in improved means for accommodating a maximum number of fowls, chickens or the like in a minimum 5 space.

An object of this invention is to provide readily accessible means for accumulating fowl or chicken manure with the least possible loss thereof.

10 Another object of this invention is to provide suitable removable roosting elements within the means for retaining the manure.

Further objects of this invention lie in the provision of means for suitably locking 15 the roosts in a set position, the general conformation of the roosts being circular and adapted to rotate when released from locked relationship. The rotation is accomplished by means of a suitable hand lever or otherwise.

20 Further objects of this invention will appear from the following detailed description and from the disclosure in the two sheets of drawings which are herewith made 25 a part of this application.

In the drawings,

Fig. 1 represents a vertical side elevational view of the roost in assembled form.

30 Fig. 2 illustrates a plan view of Fig. 1. Fig. 3 represents a side elevational view of Fig. 2 taken on line 3—3.

Fig. 4 is a perspective view of the removable roosting bar and the tray for receiving the fowl or chicken manure.

35 Fig. 5 represents a vertical sectional view of the locking lever and the spring pin for placing the lever in interlocked relationship with the rotary roost.

Figures 6 and 7 illustrate perspective 40 views of locking plates for keying roosting units together.

Fig. 8 is a perspective view of a hand lever in locked relationship with a portion of the frame of the roost preliminary to revolving 45 the roost for the purpose of cleaning or otherwise.

Numerical 1 designates the chicken wire or other suitable material forming the sides of the rotatable roost, the wire 1 being fastened 50 to the side braces 2 of the roost, the braces 2 preferably extending in spaced relationship radially from a central spindle 3, the spindle 3 being of a length approximately the width of the rotatable roost.

55 The braces or radial members 2 are ar-

ranged in spaced relationship at the ends of the central spindle 3 in such a manner as to form attaching elements or surfaces for a multiplicity of trays 4, the trays 4 being adapted to swing loosely at their ends from 60 suitable elements 5 arranged along the braces 2.

The trays 4 in this invention are arranged circumferentially of the roost every other radial member 2 having loosely carried 65 thereon, two trays 4, while the remaining radial members will have only one tray carried thereon. The trays 4 are so arranged in their relationship that they will swing freely with a proper amount of clearance to accommodate the fowls while roosting and also to allow sufficient clearance for the fowls to reach the roosting point.

Although this disclosure calls for radial members, it is to be understood that the sides 75 of the roost may be of solid material or otherwise, the trays being arranged in the manner described above.

The trays 4 are preferably constructed of light sheet metal although the type of material used in their construction will not affect the merits of the invention. The tray is preferably provided with side portions 6 and 7 with the ends open in order to retain the chicken manure in an easily accessible 85 position. The tray 4 may be provided with suitable braces 8 attached to the under surface thereof. Within the tray 4 is adapted to be placed a removable roosting bar 9 preferably made of wood of any suitable type 90 such as a bar 9, having supporting cleats 10 and 11.

In order to make it difficult or impossible for the fowls to roost on the spindle 3, a suitable guard portion 12 made of wire or otherwise 95 is adapted to surround the spindle 3, the guard portion 12 being suitably supported and spaced from the spindle 3 by means of fastening elements 13 or otherwise.

The roost is normally in a stationary position; means are provided in this invention to rotate the roost when desired, after releasing from locked position, in order to clean the device and remove the manure which is valuable for fertilizer and other purposes. 105 The locking element is loosely attached at one end by means of a pin 15 to a suitable portion of the supporting member 16 of the roost, the other end of the locking element 14 being free to move into locked relation- 110

ship wherever desired along the periphery of the roost as at 17. The device for snapping or placing the free end of the locking element 14 into locked relationship with the 5 periphery may be of any suitable type as, for example, disclosed herewith, consisting of a spring pin 18 cooperating with a spring portion 19, suitably enclosed in a container 20 which is preferably fastened to the free 10 end of the locking element 14.

In order to maintain a steady condition of the various trays when the roost is in a stationary locked position, suitable locking devices or key portions 21 and 22 are provided, 15 having notches 23 and 24 provided therein for the purpose of cooperating with suitable hook-like members 25, located at the ends of the tray portions, thereby providing efficient means for locking the roost and tray 20 portions into a steady, stationary position adapted for efficient roosting.

Any suitable means for rotating the roost when released from locked position, may be provided without affecting the merits of this 25 invention, such as a handle bar 26, having clasping fingers 27 at one end thereof for the purpose of easily connecting with the framework of the roost as at the brace 2. Obviously, the leverage provided by the detachable arm 26, will enable the roost to be easily 30 rotated for purpose of cleaning the trays, roosting bar and otherwise.

In this invention, the roosting device is 35 rotatably mounted on suitable supporting elements 16, that may be fastened into the ground or otherwise, the upper portion of the support 16 to be suitably supplied with a journal 28, adapted to carry the spindle 3 in a rotatable manner.

40 In operation this invention provides a rotatable roost upon which a maximum number of fowls may roost in a minimum amount of space and at the same time, be supplied with a proper amount of fresh air which is 45 necessary for retaining the health of the fowls.

The arrangement of the trays is such that 50 a fowl may easily reach any one of the roosting bars without unnecessary crowding or inconvenience. Many experiments and devices have been made in order to assure a maximum saving of the manure, and it is believed this device or rotatable roosts provides a tray and tray arrangement that will 55 assure practically a complete saving of the fertilizer.

It is apparent that the poultry may easily 56 assume positions on the roosts provided in this invention, as clearly shown in Fig. 2, 60 the trays and roosts are clearly open except between the ends, the poultry will jump, fly or otherwise to the desired point, for this purpose plenty of space is allowed between the trays, which are substantially held in 65 position by means of suitable locking de-

vices. No disadvantage will result from a slight tilting of the tray, when the poultry is seeking to roost.

The roost in this invention may be easily 70 rotated by hand when desired and each tray carefully cleaned after being removed from the roost or while still carried in the roost. The roost bars in this invention are also easily removed from the device and may 75 therefore be efficiently cleaned and kept sanitary.

The trays in this invention are loosely 80 hung at their ends from suitable portions of the roost and arranged alternately in spaced relationship in single and double formation 85 concentrically of the centre of the roost.

The means for locking the roost into stationary position in this invention is exceedingly simple and efficient, consisting of locking plates or key portions for the trays and 90 a locking lever for the roosting device in its assembled form.

What I claim is:

1. A rotatable roost having a multiplicity 90 of trays hung loosely from the sides thereof, roosting bars supported by the trays, means for locking the trays into substantially rigid relationship, separate means for locking the roost into a stationary position, the means consisting of suitably keyed plates having notches therein, the notches being adapted to cooperate with suitable elements at the ends of the trays.

2. A rotatable roost having a multiplicity 100 of trays hung loosely from the sides thereof, roosting bars supported by the trays, means for locking the trays into substantially rigid relationship, separate means for locking the roost into a stationary position, the means consisting of suitably keyed plates having notches therein, the notches being adapted to 105 cooperate with suitable elements at the ends of the trays, the separate means consisting of a locking bar loosely attached at one end of a suitable portion of the roost, the other end of the bar being free to establish a locked relationship at a desired point of the periphery of the roost.

3. A rotatable roost having a multiplicity 115 of trays hung loosely from the sides thereof, roosting bars supported by the trays, means for locking the trays into substantially rigid relationship, separate means for locking the roost into a stationary position, the means consisting of suitably keyed plates having notches therein, the notches being adapted to 120 cooperate with suitable elements at the ends of the trays, the separate means consisting of a locking bar loosely attached at one end of a suitable portion of the roost, the other end of the bar being free to establish a locked relationship at a desired point of the periphery of the roost, the trays being loosely swung at their ends from suitable 125 portions of the roost and arranged alter- 130

nately in spaced relationship in single and double formation concentrically of the center of the roost.

4. A rotatable roost having a multiplicity 5 of trays hung loosely from the sides thereof, roosting bars supported by the trays, means for locking the trays into substantially rigid relationship, separate means for locking the roost into a stationary position, the means 10 consisting of suitably keyed plates having notches therein, the notches being adapted to cooperate with suitable elements at the ends of the trays, the separate means consisting of a locking bar loosely attached at one end 15 of a suitable portion of the roost, the other

end of the bar being free to establish a locked relationship at a desired point of the periphery of the roost, the trays being loosely swung at their ends from suitable portions of the roost and arranged in spaced relation 20 in single and double formation concentrically of the center of the roost, manual means for rotating the roost when released from locked relationship, comprising a handle bar suitably supplied with attachable elements 25 adapted to connect with a portion of the roost.

In testimony whereof I affix my signature.

THOMAS D. CATON.
